GARMENT-PRESSING MACHINE

Herbert E. Page, Syracuse, N. Y.

Application November 20, 1936, Serial No. 111,875

9 Claims. (Cl. 38—41)

This invention relates to machines having an opening and closing movement, as garment pressing machines, including relatively movable pressing elements, as the so-called buck and head of a garment press.

More specifically it relates to machines of the type shown in my Patent No. 2,051,739 issued August 18, 1936, in which the head or movable element is closed through a quick-acting short leverage necessitating but a small movement of the actuating part, which may be the piston or piston rod of a cylinder and piston motor and goes under heavy pressure through a long leverage requiring greater movement of the piston of the cylinder and piston motor.

The ordinary pressing machine, whether power or manually operated, is constructed and designed to produce pressure between the pressing surfaces at a predetermined point, regardless of the amount of thickness of the articles being pressed.

Therefore, if, for instance, such a press is set to produce the required pressure, when it is closed, upon a piece of relatively thin material, then if it is attempted to press a thick piece of material, either the pressure is then found to be excessive or else the press is unable to complete the closing cycle at all.

In like manner, if the press is set to press a material of medium thickness, then if a thinner piece of material is substituted, the pressure will be too light, and again if a thicker piece is pressed, the pressure will be too heavy. Furthermore, the padding or thick covering which is usually used on the buck or lower pressing surface of the press wears down or gets a permanent "set" and this throws the press out of adjustment necessitating re-adjustment of the pressing machine.

Likewise, if a press is adjusted to press a thick piece of material and a thin piece is pressed, although the pressing mechanism will go through all the motions of producing heavy pressure, none will be produced.

In other words, the thickness of the material pressed on a pressing machine has a direct relation to the amount of pressure applied to said material.

In the machine of my patent, there is a time element or lost motion during the transfer from the short leverage to the long leverage and also a manual adjustment of the long leverage fulcrum is required to compensate for different thicknesses of work pieces.

One of the objects of my invention is to pro-

vide simple and efficient mechanism which will bring the pressing surfaces of the press together under relatively light pressure until the material to be pressed is encountered and the resistance of the material itself to the act of being pressed will serve to automatically shift the press mechanism from light to heavy pressure position or from short to long leverages.

Therefore, regardless of what the thickness of the material is that is being pressed, this mechanism will produce the required uniform pressure, because the material itself must be engaged between the pressing surfaces before the transfer to the heavy pressure or long leverage mechanism.

Another object is to provide a mechanism having a floating fulcrum which automatically comes into use as soon as the pressing elements encounter a substance between their pressing surfaces.

Another object is to provide means to prevent the fulcrum from coming into play, unless the head of the press is actually down upon the material to be pressed or close to the material, in what is known as safety-first position, so that if the operator's hand is caught between the pressing surfaces, heavy pressure will not be produced.

Other objects will appear throughout the specification.

The invention consists in the novel features and in the combinations and constructions hereinafter set forth and claimed.

In describing this invention, reference is had to the accompanying drawings in which like characters designate corresponding parts in all the views.

Figure 1 is a side elevation of a pressing machine embodying one form of my invention.

Figure 2 is a fragmentary detail view illustrating another embodiment of the invention.

Figure 3 is a fragmentary view illustrating a third embodiment of the invention.

Figure 4 is an enlarged fragmentary sectional view of the check valves in the oil systems shown in Figures 2 and 3.

The invention comprises, generally, a pressing machine in which the actuating or motor mechanism is connected to a lever, which carries the movable element or head, this being usually styled the yoke lever, which mechanism is connected to the yoke lever through a differential mechanism operable to successively move as a unit with, and then relatively to, the yoke lever, in order to successively apply power to the yoke

lever through a short quick-acting leverage to move the press head quickly from open position toward closed position with a relatively small movement of the actuating mechanism or part, and through a long leverage and greater movement of the actuating mechanism or part to close the press under heavy pressure, with means, as a spring or its equivalent, for normally restraining relative movement of the connections and the yoke lever, together with a second means operable during the closing movement of the press or controlled in its movement by the closing of the press or by the movement of the yoke lever for holding said differential mechanism from movement as a unit with the yoke lever, so that it moves relatively to the yoke lever when the movable element or head encounters resistance in its closing movement. As the differential mechanism or connections include a lever element, the holding means is a follow-up fulcrum controlled in its follow-up movement by the closing of the press, so that whenever the press head encounters the resistance of the lower buck or pressing element, the differential lever fulcrums on the floating fulcrum, and, under the force of the actuating mechanism, moves about its pivot relatively to the yoke lever and actuates the yoke lever to carry the head into final closed position through a long leverage.

The invention also preferably includes means for delaying the holding of the fulcrum from movement in a retrograde direction, until after the press head has traveled a predetermined distance toward closed position or has traveled into what is known as safety-first position, as before explained.

1 designates the frame of the machine which may be of any suitable construction. 2 and 3 designate respectively the lower pressing element or buck and the upper pressing element or head, the head being movable toward and from the buck 2. The buck is suitably supported on the frame or table of the machine in any suitable manner, as by the usual bracket or goose neck 4.

5 is the head carrying or yoke lever, this being pivotally mounted between its ends at 6 on an upwardly extending portion 7 of the frame in the rear of the buck 2. The head 3 is suitably carried at the end of the front arm of the yoke lever 5.

The actuating mechanism includes a suitable motor, here illustrated as a reciprocating or a cylinder and piston motor. 8 designates the cylinder, and 9 the piston rod connected to the usual piston movable in the cylinder. The cylinder is pivotally mounted at 10 to the frame to oscillate during the movement of the piston. The piston rod 9 constitutes an actuating part, which is connected through the differential connections or lever to the rear arm 11 of the yoke lever 5. The construction thus far described is substantially the same as in my patent referred to, and also the differential mechanism operated by the piston rod 9 is the same with the exception of the yielding restraining means for the differential lever and the follow-up fulcrum for the lever, to be presently described.

12 designates the differential lever pivoted between its ends at 13 to the rear arm 11 of the yoke lever, and preferably near the rear end thereof. The differential lever 12, as here illustrated, extends in a general direction lengthwise of the arm 11 of the yoke lever and its forwardly extending arm being relatively long. The piston rod 9 is pivoted at 14 to the front end of the

long arm of the differential lever 12. The rear arm of the differential lever 12 coacts with the follow-up or floating fulcrum to be presently described. The lever 12 moves as a unit with the yoke lever 5 and is movable about its pivot relative to the lever 5, when the closing movement of the press head 3 is obstructed, as when it comes against the lower buck 2 or the work thereon. The lever 12 is normally held from pivotal movement relatively to the yoke lever 5 by yielding means, here shown as a spring 15 connected at one end to the rear arm 11 of the yoke lever 5 and at its other end to the lever 12, this spring being of sufficient strength to hold the lever 12 from pivotal movement, while the yoke lever is being actuated to start in motion and carry the press head 3 from wide open position to closed position or where it encounters the resistance of the lower buck 2, or the spring is of sufficient strength to overbalance the weight of the head 3 and front arm of the yoke lever 5, plus the force required to overcome the inertia of the head and yoke lever, when the press is open.

The follow-up means, as shown in Figure 1, 25 consists of an extensible and retractile strut, here shown as including two telescoping parts 16 and 17, the part 16 being a guide pivoted at 18 to the frame and the part 17 a rod pivoted at 19 to the rear arm of the differential lever 12, so that when the press is open, the fulcrum rod 17 is telescoped to its full extent in the guide 16, as shown in broken lines in Figure 1, and when the press is closed, as shown in full lines (Figure 1), the fulcrum rod 17 is extended 35 out of the guide part 16 to nearly its full extent, and it is moved into its extended position by the actuating means or by the closing movement of the press under the action of the actuating means. As the press closes, the yoke lever 5 and differential lever 12 move as a unit from the position shown in broken lines to that shown in full lines (Figure 1), and in so doing, move the fulcrum rod 17 outwardly out of the guide part 16. The fulcrum rod 17 is held from retrograde 40 movement by suitable means shown in Figure 1, as a latch 20, coacting with any one of a series of rack teeth 21 on the fulcrum rod 17. The teeth are so located that the latch does not come into register with any one thereof, until after the press head 3 has reached the safety-first 45 closed position. Hence, if the press head encounters anything before it has reached a safety-first position, as for instance, the hand or fingers of the operator, the fulcrum rod 17 is free to 50 move retrogradely, and hence, heavy pressure will not be applied.

The latch 20 is here shown as angular in form and pivoted at its angle at 22 to a lug on the guide part 16, and as pressed into operative position, when air or motive fluid is permitted to enter the cylinder 8, and to move out of operative position, when the cylinder 8 is exhausted. The latch 20 is here shown as operated by a piston 23 in the cylinder 24 suitably supported by the guide part 16 and a piston rod 25 connecting the piston 23 and one of the arms of the latch 20. The piston 23 is actuated by motive fluid, as air, taken from the cylinder 8 through a pipe 26. The movement of the piston by the air pressure 70 is against the action of a returning spring 27. Air is admitted to and exhausted from the cylinder 8 through a combined intake and exhaust pipe 29. Any suitable control valve or valves are located in said pipe, as for instance, those shown 75

in my patent, or any other manually operated valves used in air operated power presses.

In Figure 1 is illustrated a conventional two-way valve 290 having a handle 291. When the press is open, the valve is in position to exhaust the cylinder 8 through the conduit 29 and exhaust pipe 292. When it is in operated position, the exhaust is closed and the cylinder 8 open to the intake of motive fluid through supply pipe 293.

10 The guide part 16 is adjustable relatively to its pivot 18 by reason of a slot 28 through which the pivot extends, in order to initially locate or adjust the floating fulcrum mechanism in proper position.

15 The cylinder and piston motor 8, 9 is single acting and the closing of the press is against the action of a returning spring 30.

In operation, when air is admitted to the cylinder 8 through the pipe 29, the piston therein moves outwardly, moving the piston rod 9 therewith, and applying a lifting force to the rear arm 11 of the yoke lever 5 through the differential lever 12, which is held by the spring 30 from pivotal movement, so that the press is closed 20 through a short quick-acting leverage arm represented by the radial distance between the pivots 6 and 14. During this closing movement from the broken line position to the full line position (Figure 1), the fulcrum rod 17 is moved outwardly, and when the head reaches closed or safety-first position, the latch 20 engages one of the teeth of the rack 21 and holds the fulcrum rod 17 from retrograde movement, so that now, as the differential lever fulcrums at 19 on the fulcrum rod 17, and as the head 3 has encountered the resistance of the lower pressing element or buck 2, the differential lever moves about its pivot 13 from the full line position (Figure 1) to or toward the broken line position, applying pressure through the short quick-acting leverage with a minimum consumption of power and throw of the piston and is closed through a reduction or long leverage by converting the long movement of the piston into a short powerful closing movement of the head 3. When the air is admitted to 30 the cylinder 8 through the pipe 29, some of the air pressure is transferred through the pipe 26 to the cylinder 24 which moves the latch 20 against the fulcrum rod 17 against the action of a returning spring 27, and air pressure continues to be applied, so that when the rack teeth 21 come in register with the latch 20, the latch is pressed into engagement with the rack teeth. 35

To open the press, the air is exhausted from the cylinder 8 through the pipe 29, permitting the 40 spring 30 to react and open the press. This operation also releases the pressure in the cylinder 24, permitting the spring 27 to react and withdraw the latch 20 out of holding engagement with the fulcrum rod 17.

45 In Figure 2, the press is closed through the same cylinder and piston mechanism, yoke lever and differential lever, as in Figure 1, but the floating fulcrum is shown as consisting of a dash-pot structure or two telescoping parts, one of 50 which is a cylinder, and the other a piston acting on the rear end of the differential lever 12 through a folding strut or toggle. This consists of two links 41, 42 pivoted together at 43, and one, as the link 42 being pivoted at 44 to the 55 frame, and the other at 45 to the rear arm of the

yoke lever 12, the pivot point 45 corresponding to the pivot point 19 (Figure 1).

When the press is in open position, the links 41, 42 are in their positions assumed, indicated by the broken lines (Figure 2) and when the press is closed by the action of the cylinder and piston motor, the links move into or toward straightened position, the straightened position being illustrated by the full lines in Figure 2, and when in straightened position, the differential lever 12 fulcrums and moves relatively toward the rear arm of the yoke lever 11, the same as in Figure 1, and the press goes under final pressure.

The means for holding the fulcrum parts 41, 42 from retrograde movement consists of a second extensible and retractile strut, as a cylinder 46 for a hydraulic fluid, having a piston therein and a piston rod 48 which is pivoted at 49 to one of the toggle links, here shown as the toggle link 42. One end of the cylinder is connected by a pipe 50 to a supply tank 51 for a hydraulic fluid, and the other end of the cylinder by a return pipe 52 to the tank 51. The pipe 50 has a normally open valve 53 therein, which normally permits the flow of oil therethrough in both directions, and is operable to permit the flow of oil therein in one direction or from the tank 51 into the cylinder and prevent retrograde movement of the oil from the cylinder back through the pipe 50 into the tank. The valve 30 is operable to check retrograde movement of the oil by an air operated instrument, as a diaphragm in a diaphragm chamber 54, the pressure side of the diaphragm chamber being connected by a pipe 55 to the cylinder 8, this corresponding to 35 the pipe 26 (Figure 1). The other side of the diaphragm is operable through part or stem 56 (Figure 4) on the valve head 530 to move it into closed position to check retrograde movement of the oil. The movement of the diaphragm under 40 pressure is against a returning spring 57. The valve head 530 is formed with passages 531 there-through, which passages are closed by a spring-pressed check valve or disk 532 located to prevent back-flow of oil through the passages 531. When 45 air is admitted to the cylinder 8 through pipe 29, air also passes through pipe 55 to the diaphragm chamber, moving the valve head 530 into closed position against its seat, but oil is free to flow from the tank through the pipe 50 past the valve 50 through the passages 531, displacing the disk 532 against the spring 533. However, under back pressure of the oil in the pipe 50, the disk 532 closes the passages 531 and as the valve head 530 is seated, retrograde movement of the oil from the cylinder 46 and hence retrograde movement of the piston rod 48 and the links 41, 42 and lever 12 is prevented.

As the press closes under the action of the 60 cylinder and piston motor 8-9, the links 41, 42 move toward the straight line position shown by full lines (Figure 2), and in so doing, move the piston and its rod 48 toward the right (Figure 2). During this movement, the piston rod 48 65 moves the oil in front of it through the pipe 52 to the tank 51 and the oil from the tank 51 is free to flow through pipe 50 to the rear side of the piston and follow up the piston. However, retrograde movement of the oil back into the tank 70 is prevented by the valve 53, which has been operated, when the air is admitted to the cylinder 8 through pipe 29. Thus, when the head encounters the resistance of the buck, the power of the cylinder and piston motor actuates the 75

differential lever 12 relative to the yoke lever and applies heavy pressure.

When the press is to be opened, air is exhausted through the pipe 29 from the cylinder 8, also, exhausting air from the diaphragm chamber 54, so that it permits the valve 53 to be moved by its spring 57 into position to permit back flow of oil through the pipe 50. As the press is opening under the influence of the spring 30, the piston on the rod 48 is moved retrogradely in the cylinder 46 and transfers the oil from behind the piston 46 through the pipe 50 back to the tank 51. It also flows retrogradely from the tank 51 through the pipe 52 to in front of the piston and follows up the piston during its retrograde movement.

An overload valve 59 is provided in a by-pass 60 around the valve 53, this overload valve being adjusted to permit the retrograde flow of oil from the pipe 50 through the pipe 60 to the tank 51 around the valve 53, when the pressure between the pressing elements 2, 3 becomes excessive or above a desired maximum. This might occur when extremely thick work pieces were being pressed or a new thick padding on the buck 2 was being used. The overload valve is of any well known construction, as for instance, the overload valves used in the lubricating system of internal combustion engines.

30 In the construction shown in Figure 2, resistance to retrograde movement of the piston 48 takes place as soon as the air is admitted to the cylinder 8 to close the press.

In Figure 3, the resistance of the retrograde movement does not become effective, as in Figure 1, until the press head is closed to a safety-first position.

In Figure 3, 61 and 62 designate the telescoping parts corresponding to the parts 16 and 17 (Figure 1), these being a cylinder and a piston rod, the latter being connected to the piston 63 in the cylinder. The cylinder 61 is pivoted at 64 to the frame of the machine, and the piston rod 62 is pivoted at 65 to the rear arm of the differential lever 12, this corresponding to the pivot point 19 (Figure 1).

66 is a tank for a hydraulic fluid, this being connected by outlet pipes 67, 68 to a port 69 at the end of the cylinder 61 remote from the end 50 through which the piston rod 62 extends. 70 is a return pipe from the end of the cylinder remote from the port 69 back to the tank 66. 71 is a by-pass opening into the cylinder 61 through a port 72 between the ends thereof, and preferably located near the end remote from the intake port 69, this pipe communicating with the pipe 68. A valve 73 similar to the valve 53 (Figure 4) is located at the juncture of the outlet pipes 67, 68 of the oil tank 66. This valve 73 is operated by a 55 diaphragm in a chamber 74. The pressure side of the diaphragm chamber is connected by a pipe 75 to the cylinder 8, the pipe 75 corresponding to the pipe 26 (Figure 1).

In operation, when air is admitted through the pipe 29 to the cylinder 8, air is also admitted to the diaphragm chamber 74, operating the valve 73 to check back-flow of oil from the cylinder 61 to the tank 66. However, as the piston 63 is drawn to the right hand end of the cylinder 61 by the closing movement of the press, the oil in front of the piston or on the right hand side thereof is free to flow through the pipe 70 back to the tank, and also incidentally through the by-pass 71 back to the pipe 68. However, if the 70 press head 3 encounters resistance before it

reaches a safety-first position, any differential movement of the lever 12 would not be transferred to the yoke lever 5, but would be transferred to the piston rod 62, which is free to move in a retrograde direction, by circulating the oil 5 retrogradely through the pipe 68 and by-pass 71 and port 72 around the piston 63, as the piston has not yet passed port 72, and hence, heavy pressure will not be applied to the press head 3. The mechanism is so timed that when the head 10 10 reaches safety-first position, the piston 63 has passed to the right, beyond the port 72, so that oil can not pass from one side of the piston to the other through the by-pass 71, and hence, the differential lever 12 is free to pivot relatively to 15 the yoke lever 5 or the rear arm thereof and apply heavy pressure.

If it is desired to have the press go under final pressure at any time the head 3 encounters resistance, a check valve 80 similar to the valve 53 20 (Figures 2 and 4) may be placed in the pipe 68 between the by-pass 71 and the port 69. The pressure side of the diaphragm chamber 81 of this valve is also connected, as by a pipe 82, to the cylinder 8. This valve, when used, in effect, cuts out the by-pass 71. The pipe 82 has a suitable cut-out valve 83 therein. When the cut-out valve 83 is adjusted to open position, and air is admitted through the pipe 29 to the cylinder 8, the valve 73 is operated to prevent back-flow into the tank 66 and also the valve 80 is operated to prevent back-flow through the by-pass 71, so that the press operates as if no by-pass 71 were employed. As the press closes under the action of the cylinder and piston motor 8-9, the piston 63 35 moves to the right, and the oil on the right hand side of it, during this movement, is returned to the tank 66 through the return pipe 70, but retrograde movement of the piston 63 and the oil back through the port 69 to the by-pass 74 is prevented by the valve 80. The use of this valve 80 is referred to primarily as showing one form of follow-up fulcrum that becomes effective at any point the head 3 may encounter resistance between wide open and closed position and also to 40 show means of cutting out the safety-first provision, in the event it may be desirable to operate the machine without the safety-first provision, as for instance, in pressing an abnormally thick goods or layers of abnormally thick goods. When 45 the machine is adjusted to eliminate the safety-first feature, the valve 73 functions to prevent the back-flow of oil through the by-pass 71 to the tank through the outlet pipe 67. An overload valve and by-pass, similar to the valve 59 and by-pass 60 (Figure 2) may be installed in the pipes 67, 68 around the valves 73, 80. The overload valves are of the same nature as those used in the lubricating systems of automobile engines. 50

In any form of my invention, the differential lever 12 instead of fulcruming at any fixed point requiring mechanically adjustable fulcrums, as in my patent referred to, fulcrums at any point the press head 3 encounters resistance of the lower buck, and also this point can be located 55 within the safety or "safety-first" limits. By reason of the follow-up fulcrum in any of its forms, there is no lost motion or time element between when the head encounters the buck and when the differential lever acts. 60

70 What I claim is:

1. In a garment pressing machine, the combination with a suitable frame, cooperating pressing elements, one of which is movable toward and from the other, a lever pivoted between its ends 75

- to the frame and carrying the movable element on one arm thereof, actuating mechanism for the lever including an actuating part, a differential lever connected to the actuating part, pivoted between its ends to the other arm of the lever, and operable to successively move as a unit with, and relatively to, said lever to successively apply power to the first lever through a short quick-acting leverage to move the movable element from open position toward closed position with relatively small movement of the actuating part, and through a long leverage and greater movement of the actuating part to close the press under heavy pressure, and means for normally restraining relative movement of the first lever and the differential lever; of follow-up normally idle fulcrum means for the differential lever coacting with the differential lever and operable by the closing of the press to follow said differential lever as it moves as a unit with the first lever, means controlled by the closing of the press for holding the fulcrum means from retrograde movement, all whereby when the movable element encounters resistance sufficient to overcome said restraining means, the differential lever moves about its pivotal axis and fulcrums on said fulcrum means.
2. In a garment pressing machine, the combination with a suitable frame, cooperating pressing elements, one of which is movable toward and from the other, a lever pivoted between its ends to the frame and carrying the movable element on one arm thereof, actuating mechanism for the lever including an actuating part, and connections between said part and the other arm of the lever and operable to successively move as a unit with, and relatively to, said lever to successively apply power to the lever through a short quick-acting leverage to move the movable element from open toward closed position and through a relatively long leverage and greater movement of the actuating part to close the press under final pressure, said connections including a differential lever element, and means for normally restraining relative movement of said connections and the lever; of fulcrum means for coacting with said lever element and operable by the closing movement of the press for effecting, in conjunction with the actuating part, relative movement of said connections and the first lever against the restraining means, when the movable element encounters resistance in its closing movement, the fulcrum means including two telescoping parts, one being connected to said lever element to move therewith, when said connections are moving as a unit with the first lever, and means controlled by the closing movement of the press for holding the movable telescoping part from retrograde movement.
3. In a garment pressing machine, the combination with a suitable frame, cooperating pressing elements, one of which is movable toward and from the other, a lever pivoted between its ends to the frame and carrying the movable element on one arm thereof, actuating mechanism for the lever including an actuating part, and connections between said part and the other arm of the lever and operable to successively move as a unit with, and relatively to, said lever to successively apply power to the lever through a short quick-acting leverage to move the movable element from open toward closed position and through a relatively long leverage and greater movement of the actuating part to close the press under final pressure, said connections in-

cluding a differential lever element, and means for normally restraining relative movement of said connections and the lever; of fulcrum means for coacting with said lever element and operable by the closing movement of the press for effecting, in conjunction with the actuating part, relative movement of said connections and the first lever against the restraining means, when the movable element encounters resistance in its closing movement, said fulcrum means comprising telescoping parts, one being a dash-pot cylinder, the other a piston in the cylinder and having its rod connected to the lever element, means controlled by the closing movement of the press for controlling the flow of a fluid to the dash-pot cylinder to the rear side of the piston and trapping the same in the cylinder to hold the piston rod from retrograde movement.

4. In a garment pressing machine, the combination with a suitable frame, cooperating pressing elements, one of which is movable toward and from the other, a lever pivoted between its ends to the frame and carrying the movable element on one arm thereof, actuating mechanism including a cylinder and piston, and connections between the rod of the piston and the other arm of the lever and operable to successively move as a unit with, and relatively to, said lever to successively apply power to the lever through a short quick-acting leverage to move the movable element from open toward closed position and through a long leverage to close the press under heavy pressure, said connections including a lever element, and means for normally restraining movement of said connections and the first lever; of follow-up fulcrum means including a dash-pot having a movable piston member connected to said lever element and movable therewith as the press closes, a fluid supply for the dash-pot, a conduit connecting said supply with the dash-pot on one side of the piston member, and a return conduit from the dash-pot from the other side of the piston member, a normally open check valve in the supply conduit to the dash-pot, fluid operated means for operating the check valve into position to prevent back flow from the dash-pot to the supply, and conduit means for supplying motive fluid to and from the cylinder of the actuating means and said fluid operated means for the check valve.

5. In a garment pressing machine, the combination with a suitable frame, cooperating pressing elements, one of which is movable toward and from the other, a lever pivoted between its ends to the frame and carrying the movable element on one arm thereof, actuating mechanism including a cylinder and piston, and connections between the rod of the piston and the other arm of the lever and operable to successively move as a unit with, and relatively to, said lever to successively apply power to the lever through a short quick-acting leverage to move the movable element from open toward closed position and through a long leverage to close the press under heavy pressure, said connections including a lever element, and means for normally restraining movement of said connections and the first lever; of follow-up fulcrum means including a dash-pot having a movable piston member connected to said lever element and movable therewith as the press closes, a fluid supply for the dash-pot, a conduit connecting said supply with the dash-pot and a return conduit from the dash-pot to

the supply, said conduits opening into the dash-pot on opposite sides of the piston member, a normally open check valve in the supply conduit to the dash-pot, fluid operated means for operating the check valve into position to prevent back flow from the dash-pot to the supply, a bypass having an overload valve therein around the check valve, and conduit means for supplying motive fluid to and from the cylinder of the actuating means and said fluid operated means for the check valve.

6. In a garment pressing machine, the combination with a suitable frame, cooperating pressing elements, one of which is movable toward and from the other, a lever pivoted between its ends to the frame and carrying the movable element on one arm thereof, actuating mechanism including a cylinder and piston, and connections between the rod of the piston and the other arm of the lever, and operable to successively move as a unit with, and relatively to, said lever to successively apply power to the lever through a short quick-acting leverage to move the movable element from open toward closed position and through a long leverage to close the press under heavy pressure, said connections including a lever element, and means for normally restraining movement of said connections and the first lever; of follow-up fulcrum means including a dash-pot having a movable piston member connected to said lever element and movable therewith as the press closes, a fluid supply for the dash-pot, a conduit connecting said supply with the dash-pot and a return conduit from the dash-pot to the supply, said conduits opening into the dash-pot on opposite sides of the piston member, a normally open check valve in the supply conduit to the dash-pot, fluid operated means for operating the check valve into position to prevent back flow from the dash-pot to the supply, and a by-pass communicating with the dash-pot through ports at spaced apart points with respect to the movement of the movable member of the dash-pot when the dash-pot is in normal position for permitting free displacement during a portion of the closing movement of the press and arranged to be passed by the piston member during the final closing of the press, whereby said ports are located on the same side of the piston member, when the press is under final pressure, and conduit means for supplying motive fluid to and from the cylinder of the actuating means and said fluid operated means for the check valve.

7. In a pressing machine including an element having an opening and closing movement, mechanism for effecting the opening and closing movement including a lever pivoted between its ends, one arm thereof serving to transmit the motion of the lever to the movable element and actuating mechanism for the lever including an actuating part, and connections between said part and the other arm of the lever and operable to successively move as a unit with, and relatively to, said lever to successively apply power to the lever through a short quick acting leverage with rela-

tively small movement of the actuating part and through a long leverage and greater movement of the actuating part, the connections including means by which the relative movement thereof is transferred to said lever, means for normally restraining relative movement of said connections and the lever, a second means operable by the closing movement of the press for effecting, in conjunction with the actuating part, relative movement of the lever and said connections against the restraining means when the movable element encounters resistance in its closing movement, and control means for the actuating mechanism.

8. In a pressing machine, the combination of a suitable frame, cooperating pressing elements, one of which is movable toward and from the other, mechanism for actuating the movable element including a lever pivoted between its ends and one arm thereof serving to transfer movement to the movable element, actuating mechanism for the lever including an actuating part, a differential lever pivoted between its ends to the other arm of the first lever and operable to successively move as a unit with, and relatively to, the first lever, means for normally restraining relative movement of the first lever and the differential lever and follow-up fulcrum means for the differential lever, said fulcrum means being operable by the closing of the press to follow up said differential lever as it moves as a unit with the first lever, means for holding the fulcrum means for retrograde movement, all whereby when the movable element encounters resistance, the differential lever fulcrums on the follow-up fulcrum and moves about its pivot relatively to the first lever against the restraining means and control means for the actuating mechanism and said means for holding the follow-up fulcrum from retrograde movement.

9. In a garment pressing machine, the combination with a suitable frame, cooperating pressing elements, one of which is movable toward and from the other, a lever pivoted between its ends to the frame and carrying the movable element on one arm thereof, actuating mechanism for the lever including an actuating part, a differential lever pivoted between its ends to the other arm of the first lever, one arm of the differential lever being connected to said part, means for normally restraining relative movement of the first lever and the differential lever, so that the first lever and the differential lever are normally held from relative movement by the restraining means; of normally-idle follow-up fulcrum means coacting with the other arm of the differential lever and operable by the closing of the press to follow said differential lever, as it moves as a unit with the first lever, means for holding the fulcrum means from retrograde movement in its follow-up movement, and operator-operated means for controlling the operation of the actuating mechanism and the fulcrum holding means.
